UNITED STATES PATENT OFFICE.

CHARLES A. CONGER, OF OAKLAND, CALIFORNIA.

DESIGN FOR A CONDIMENT-SHAKER.

42,271.

Specification for Design. Patented Mar. 12, 1912.

Application filed December 7, 1911. Serial No. 664,499. Term of patent 14 years.

To all whom it may concern:

Be it known that I, CHARLES A. CONGER, a citizen of the United States, residing at Oakland, county of Alameda, State of California, have invented a new, original, and ornamental Design for a Condiment-Shaker, of which the following is a specification, reference being had to the accompanying drawings, forming part thereof.

Fig. 2 is a top, plan view of the same. Fig. 3 is a bottom view.

I claim:

The ornamental design for a condiment shaker, as shown.

CHARLES A. CONGER.

Witnesses:

JOHN H. HERRING,
FRANCES V. COLE.
